UNITED STATES PATENT OFFICE.

FREDERICK P. WOOD, OF OAK PARK, ILLINOIS, ASSIGNOR TO AMERICAN CAN COMPANY, OF NEW YORK, N. Y., A CORPORATION OF NEW JERSEY.

PAPER CONTAINER.

1,333,746.

Specification of Letters Patent. Patented Mar. 16, 1920.

Application filed May 28, 1915. Serial No. 30,914.

To all whom it may concern:

Be it known that I, FREDERICK P. WOOD, a subject of the King of Great Britain, residing in Oak Park, in the county of Cook 5 and State of Illinois, have invented a new and useful Improvement in Paper Containers, of which the following is a specification.

This invention relates in general to containers and has more particular reference to paper or fibrous containers of the character described in my pending application filed March 5, 1915, Serial No. 12,806.

A principal object of this invention is the 15 provision of an effective sealing means for securing a frangible closure in the otherwise open end of such and similar containers.

A further object of this invention is the 20 provision of a readily applied adhesive or cement for securing a frangible closure in place.

Other objects and advantages of the invention will be apparent as it is better understood from the following description when considered in connection with the accompanying drawing illustrating a preferred embodiment thereof.

Referring to the drawing,

30 Figure 1 is a side elevation of a container embodying my invention shown partially in section;

Fig. 2 is a top plan view thereof with the frangible cover removed;

35 Fig. 3 is a detailed section showing the adhesive in position and the body ready to receive the frangible closure; and

Fig. 4 is a similar view of the same matter with the frangible cover in place.

40 Fig. 5 is a perspective view of the frangible closure.

For the purpose of illustrating my invention I have shown it embodied in a container of the well known cylindrical form.

45 This container consists of a body A, a frangible closure C and an outer or friction closure D. The body in the present instance consists of a cylinder formed by winding a continuous strip of paper or the like suitably fastened together to render the cylinder stiff. The cylinder thus formed is provided with an inwardly extending bead or depression 6 near one end, which bead or depression is collapsed after being formed 50 to bring the edges 7 of the depression sub-

stantially into contact so that the outer surface of the container consists of a substantially smooth unbroken plane and so that the structure and the bead or flange thus formed is further stiffened. A cardboard ring 8 is positioned against the collapsed bead 6 and the upper edge 9 of the body is curled over and rests upon the upper surface of the ring 8. The ring 8 forms a flange member adapted to be engaged by a cover or closure member, as will be later described. The parts arranged as set forth may receive a proofing rendering it impervious to the matter it is to contain. The closure consists of the frangible disk C preferably of paper, which may or may not be proofed with the same material as the body. This frangible disk may be held in place by an annular body or adhesive 10 shown in the present instance as seated in an annular depression 11 formed in the flange member or ring 8. This adhesive is fed in in any suitable manner and the edges of the depression substantially define it within desired limits. Therefore the frangible closure is placed into position and pressed down into contact with the flange member or ring 8 where it is held by the adhesive. A friction closure D is inserted within the curled over edge 9 which overhangs and holds it in place, as seen in Fig. 1. The friction closure D serves to protect the frangible closure against premature fracture.

It is thought that the invention and many 90 of its attendant advantages will be understood from the foregoing description, and it will be apparent that various changes may be made in the form, construction and arrangement of the parts without departing 95 from the spirit and scope of the invention or sacrificing any of its material advantages, the form hereinbefore described being merely a preferred embodiment thereof.

I claim:

1. A container comprising a paper body having its wall bent inward to form a bead, and the edge of said wall curled over inward and extending downward to near said bead, an open fibrous ring permanently secured between said bead and the under side of the bottom end of said curled over edge and extending inward beyond the latter, a frangible seal permanently attached on the inner part of said ring over the opening thereof, 110

and an outer closure removably held frictionally against the inner face of said curled over edge of the body.

2. A container comprising a body having an inwardly extending flange near its top, said flange being provided with an annular depression, adhesive seated in said depression and a cover member held in place by said adhesive.

10 3. A container comprising a paper body having its wall bent inward and formed into a solid bead of double thickness having its edge curled over inward and downward to near said bead, an open fibrous ring secured 15 permanently between said edge of the body and said bead and extending inward beyond the bead, and a removable fibrous closure supported by the inner part of said ring and held frictionally by the inner surface of said 20 curled over edge of the body.

4. A paper container comprising a body which is bent inwardly and outwardly near its top to produce a shoulder, an inwardly extending ring seated on said shoulder, the 25 edge of the body being bent inwardly and downwardly and permanently confining said ring, a frangible cover member seated on said ring and permanently secured thereto, and a removable outer cover frictionally 30 held in place on said frangible cover and engaged partly under the inner outwardly inclined face of the bent end of the body.

5. A paper container comprising a body which is bent inwardly and outwardly near

its top to produce a shoulder, an inwardly 35 extending ring seated on said shoulder, the edge of the body being bent inwardly and downwardly and permanently confining said ring, said ring being provided with a ring of adhesive, a frangible cover member seated on said inwardly extending ring and permanently held in place by said adhesive, and an outer removable cover frictionally held in place on said frangible cover and engaged partly under the inner outwardly inclined face of the bent end of the body.

6. A paper container comprising a body which is bent inwardly and outwardly near its top to produce a shoulder, an inwardly extending ring seated on said shoulder, the 50 edge of the body being bent inwardly and downwardly and permanently confining said ring, said ring being provided with an annular depression, a ring of adhesive seated in said depression, a frangible cover member seated on said ring and permanently held in place by said adhesive, a removable outer cover frictionally held in place on said frangible cover and engaged partly under the inner outwardly inclined face of the bent 55 end of the body.

Signed in the presence of two subscribing witnesses.

FREDERICK P. WOOD.
